ARTHUR D. COPPERTHWAIT, OF WATERBURY, CONNECTICUT, ASSIGNOR TO SCOVILL MANUFACTURING COMPANY, OF WATERBURY, CONNECTICUT, A CORPORATION OF CONNECTICUT

GANG CONDENSER

Application filed July 20, 1929. Serial No. 379,617.

This invention relates to improvements in variable electric gang condensers.

It is an object of the invention to provide means for equalizing the potentials of the 5 rotors of the individual condensers and improve the shielding between condensers.

With these general objects in view, the invention consists in certain features, combinations, details of construction, and arrangements of parts which will first be described 10 in connection with the accompanying drawings and then more particularly pointed out.

In the drawing:

Figure 1 is a plan view of a gang condenser constructed in accordance with the 15 present invention;

Figure 2 is a cross-sectional view taken as on line 2—2 of Figure 1; and

Figure 3 is a sectional view taken as on 20 line 3—3 of Figure 1.

Referring in detail to the embodiment chosen to illustrate the invention, the gang condenser comprises a frame having a bottom 10, side walls 11 and end walls 12, said frame being open at the top. The frame may be composed of any suitable conducting metal, but generally brass or steel. Within the frame a plurality of condenser units are disposed. As here shown, the condenser units 25 comprise rotors 13, mounted on sleeves 9 fitted tightly on a common rotor shaft 14, and stators 15 mounted within and supported by the frame but insulated therefrom. The rotors and stators illustrated comprise spaced 30 parallel plates adapted to be interleaved varying amounts upon rotation of the shaft and shaped so as to impart to the condenser a characteristic law of capacity variation. In the exemplification, the rotor shaft is 35 journaled in the end walls of the frame and the rotors are connected electrically to said frame through said shaft. One end of the shaft projects beyond its end wall for attachment of an operating device, such as a dial 40 (not shown) or other means for rotating the shaft. The rotor shaft is preferably provided with a friction brake, generally indicated at 16, for producing a regulative frictional force retarding rotation of the shaft. 45

50 This general form of gang condenser con-

struction is already known and in use. It has been found however, that there are electrostatic reactions between the individual condenser units and that the rotors of said units are not equalized as to potential, the 55 difference being due to potential drops along the rotor shaft.

The invention, in its entirety, embodies shielding means for increasing the air paths between the condenser units to extents substantially to inhibit electrostatic reactions 60 between them. Although capable of various constructions, as here shown by way of example, shielding plates 17 of metallic conducting material are placed between the condenser units transversely across the frame. In the example, the plates are provided with 65 slots 18 for the accommodation of the side walls of the frame, and with lugs 19 on the bottom edges serving as tenons for engaging with corresponding apertures or mortises in the bottom side of the frame. The lugs may be soldered in their apertures or otherwise secured therein. The shielding plates are thus secured in place, and electrically connected to the frame. The rotor shaft, 14, extends through openings in the 70 shielding plates and, as shown, the plates project appreciably above said shaft and are 75 sufficiently large substantially to prevent electrostatic reactions in the air between condenser units. The air paths between condenser units are, in effect, increased by the shielding plates to amounts such that electrostatic reactions through the air paths are 80 practically eliminated. Although capable of some variations, for best results, the plates should extend above the shaft distances at least equal to the heights and points reached 85 by the rotors on rotation so as to prevent straight air paths between the rotors at any of their positions. Parts 20 of the shielding plates overlap the exteriors of the side walls of the frame to an amount sufficient to 90 substantially prevent electrostatic communication between those portions of the stators on the outside of the side walls of the frame. 95

The invention also includes means for equalizing the potential between the rotors of the individual condensers. This may con- 100

veniently be accomplished by electrically connecting the rotors to the shields. Although capable of various constructions, in that here shown as an example, the rotors are electrically connected to the shielding plates by clips 21 which are pressed between the shields and the ends of the rotor sleeves. As here shown, the clips are of thin sheet metal, of bowed, resilient nature so as to be compressed in place and firmly engage the shields and sleeves to establish good electrical contacts. The clips are formed as with slots 22 in order to slip over the rotor shaft into proper positions and are held in such positions by suitable means, such, for example, as lugs 23 on the clips which enter recesses or perforations 24 in the shields. This construction allows a clip conveniently to be slipped in place or withdrawn.

20. What is claimed is:

A variable condenser comprising a conducting frame, a plurality of variable condenser units within the frame embodying stators supported by the frame and insulated therefrom, rotors, sleeves on which the rotors are mounted and a common shaft on which the sleeves are fitted, conducting shielding plates between condenser units and electrically connected to the frame, and 25 bowed, resilient conducting clips pressed between the shielding plates and sleeve ends for connecting electrically the sleeves to the plates, each clip having end portions engaging the shielding plates and intermediate portions engaging said rotors, a clip bearing on each side of each of said shielding plates and exerting pressure on said rotors in opposite directions.

30 In testimony whereof, I have hereunto set
40 my hand.

ARTHUR D. COWPERTHWAIT.
